PICTURE TRANSMISSION AND RECEPTION
SYSTEMClinton W. Hough, Boonville, N. Y., assignor, by
mesne assignments, to Wired Radio, Inc., New
York, N. Y., a corporation of Delaware

Application June 12, 1928, Serial No. 234,768

8 Claims. (Cl. 178—6)

My invention relates to the transmission and reception of motion pictures by means of either space radio or wired radio systems.

An object of my invention is to provide a system for simultaneous transmission and reception of a group of successive pictures.

Another object of my invention is to provide a method of scanning each individual picture "frame" of a motion picture film and a means 10 for scanning a beam of light in the means for reception.

A further object of my invention is to provide a method of scanning each individual picture "frame" or for duplicate scanning each picture "frame" or alternate picture "frames" in both 15 transmitter and receiver.

Still a further object of my invention is to provide a system for reproducing colored images and projecting the picture or image on a screen 20 or on another motion picture film, in the natural colors.

Other and further objects of my invention are shown in the following specification and in the accompanying drawings, in which:

25 Figure 1 illustrates the apparatus I employ in the transmission of motion pictures.

Fig. 2 illustrates the scanning wheel I employ in the apparatus of my invention.

Fig. 3 shows further details of the scanning 30 wheel or band and illustrates the perforations for interrupting or scanning.

Fig. 4 shows further details of the perforations in the scanning wheel or band.

Fig. 5 illustrates the relative spacing of the 35 perforations in the scanning wheel or band.

Fig. 6 illustrates a synchronizing method and the system I employ for the reception of motion pictures.

40 Figs. 7 and 8 are diagrammatic illustrations of my system for the transmission and reception of motion pictures, by space radio and wired radio systems respectively.

In the embodiment of my invention herein shown and described, certain features constitute subject matter for a separate invention in accordance with my co-pending application, Serial No. 391,039, filed September 7, 1929, now Patent No. 1,972,444, granted Sept. 4, 1934.

45 In Fig. 1 of the drawings the transmission apparatus is mounted on a base 1. Base 1 has an upstanding member 36 upon which are mounted film reels 5 and 6. A case 14 for the motor 2 together with reflector 8, projection lamp 9, and condensing lens 10, is mounted on the common base 1. A base 3 supporting motor 2, reflector

8, projection lamp 9 and condensing lens 10 is mounted on case 14. An upstanding member 36 supports driving mechanism for reels 5 and 6, and film 46. The driving mechanism includes motor 2, chain or belt 15, pulleys and sprockets 4 and 7 and Geneva star or cam movements 16. Upstanding member 36 supports in addition to the driving mechanism for film 46, focusing lens 11 and light sensitive cell 12 enclosed by cover 51. An opening 17 is provided through the case 14 10 and is of similar dimensions to one picture "frame" of film 46.

In Fig. 2 of the drawings, the scanner wheel 22 has an upstanding rim 23 which is perforated to interrupt the rays of light. Scanner wheel 22 is 15 made rigid by ribs 24 pressed therein. A hub 30 has a key 20 whereby the exact position of scanner wheel can be determined in respect to the lens and other equipment, thus enabling synchronization of both transmission and reception equipment.

Fig. 3 shows the scanner wheel 22 and scanner band 23 with perforations 21, the perforations being arranged in a width 25 on the band 23 corresponding to the width of the film "frame". A hub 30 and hole 29 indicate the mounting of the scanner wheel 22 on the shaft of the motor 2 illustrated in Fig. 1. 28 represents the circular degree of perforations while 26 represents that portion of the band 23 which is opaque or not 30 perforated.

Figs. 4 and 5 show the scanner band 23 of scanner wheel 22 in greater detail. The reference characters here are the same as those of Fig. 3 wherein, 23 represents the scanner band in its 35 entirety, 25 represents the width of the area 28 which is perforated. The perforations 21 are spaced along a diagonal line and spaced the height of the film frame. The portion 26 is opaque and not perforated and constitutes 25% 40 of the circular measure of the scanner band 23. The scanner band 23 is a development of scanner wheel 22 although it might be otherwise constructed of suitable material and secured to the scanning wheel by rivets or machine screws.

45 Fig. 6 shows the receiving apparatus and includes a base 1 similar to the base 1 of the transmitter illustrated in Fig. 1. A case 14 is mounted on base 1 and supports the sub-base 3 upon which are mounted motor 2, reflector 8, high frequency 50 arc light or glow discharge tube 40 and condensing lens 48. An upstanding member mounted on base 3 supports an adjustable shaft 41 for adjusting the apparatus in synchronism with the transmitting apparatus. Shaft 41 has a knob or dial 55

- 42 for synchronization adjustment. Scanner wheel 22 is mounted on the shaft of motor 2 and movable therewith. Inclosure case 14 also provides a support for focusing lens 11 and color filter 5 44. Color filter 44 is mechanically connected with the shaft of motor 2 by shaft 43 and is adjusted for synchronization with scanning wheel 22. Color filter 44 intercepts light rays projected on the screen 45.
- 10 A method of synchronizing that may be employed with my system for transmission and reception is also shown. Scanning wheel 22 is shown with scanning band 23. The opaque portion 26 of scanning band 23 is illustrated as constituting 15 a 90° arc of $\frac{1}{4}$ the circumference of scanning band 23. Synchronizing magnet 31 is mounted on scanning wheel 22. Synchronizing coil system 32 is stationary and may be mounted on the scanning wheel case 14.
- 20 Fig. 7 is a diagrammatic illustration of my system for transmission and reception of motion pictures by space radio, reference numbers corresponding to those in the preceding Figs. 1 and 6. Variations of current are amplified and modulate 25 the output of the space radio transmitter.
- Fig. 8 is a diagrammatic illustration of my system for the transmission and reception of motion pictures by wired radio, reference numbers corresponding to those in Figs. 1 and 6. Variations of 30 current are amplified and caused to modulate the output energy of a wired radio transmitter. The wired radio transmitter is connected electrically with the receiver.
- The operation of my system for the transmission 35 and reception of motion pictures and for the transmission and reception of colored motion pictures is as follows: In the transmitter, the positive film 46 is mechanically moved down past a rectangular opening 17 corresponding to the 40 size of the "frame" or individual picture on the film. The film 46 is moved continuously at the points where it leaves the supply reel 5 and where it enters the receiving reel 6 after projection. Between the points where the film leaves 45 the supply reel and where it enters the receiving reel there are two loops formed in the film. These loops allow sufficient slack in the film so that the central section of the film between the supply and receiving reels may be moved intermittently without putting any strain on the 50 film. This central section of film 46 is moved continuously at the two outward ends of the two loops by means of uniformly rotating sprocket wheels 7 the teeth of which mesh with perforations 55 in the outer edges of the film 46. At the two sprocket wheels 7 the film moves uniformly forward through the projector. Between the two sprocket wheels is an intermittent movement operated by a cam or Geneva star mechanism 16. 60 The metal fingers of this movement engage the perforations in the edge of the film and each operation moves the film down exactly one "frame" or picture. The standard speed of projection is at the rate of sixteen "frames" per second. The 65 opaque section 26 of scanning band 23 cuts off the projecting light during the downward movement of the film. The film is then held stationary and the perforated section 25 of the scanning band 23 allows the light to be projected through 70 the picture and on the light-sensitive cell 12. The opaque portion 26 of the scanning band 23 shuts off the light and the film is again moved down one frame and the cycle repeated. At the 75 rate of sixteen projections per second, the time required for a complete cycle is $4/64$ second.

Of this, roughly 1/64 second is devoted to the movement of the film and during this interval the light sensitive cell 12 is dark. 3/64 second is devoted to the projection. This means that each individual "frame" of the motion picture film 46 must be scanned, transmitted, received and reproduced in 3/64 second. The synchronizing function may be operated during the 1/64 second interval when no picture is being transmitted.

The scanning wheel and band of my invention combines the shutter with the scanner and is employed at both the transmitter and the receiver. Referring to Figs. 2, 3 and 4, my scanning device consists of a wheel 22, or it may be 15 a disc or band 23 of opaque material in which are a series of small perforations 27 for the transmission of light. If the film is moved in the time cycle above outlined, then 25% of the periphery of the wheel, disc or length of the band, is 20 opaque, without any perforations. 75% of the periphery is provided with small openings arranged diagonally on the band along a curved line of uniformly increasing distance from the center of a disc or diagonally around the circumference of the flange rim of a wheel. Vertically they are spaced the distance apart corresponding to the height of the motion picture "frame" and horizontally they are spaced so that each successive opening joins the space occupied by 30 the previous opening and the total number of openings correspond to the width of the "frame" opening. The successive openings are therefore so positioned that in moving over the rectangular "frame" opening corresponding to the picture 35 area all portions of the picture will be successively subject to a light beam which is varied in intensity by being reduced in brilliancy in proportion to the density of the picture film and will therefore correspond in intensity to the 40 point of the picture in the path of the beam. The varying intensity beam is focused on to a light sensitive cell and correspondingly varies the energy flowing in its electrical output circuit. This output energy is amplified by means of 45 audion amplifiers and operates to modulate the carrier wave of a space radio or wired radio transmitter.

For the transmission of colored motion pictures alternate successive frames of the film are 50 exposed through complementary color screens or filters, the even numbered frames through one filter and the odd numbered frames through the second filter. As this is done when the picture is made in the original camera exposure the 55 preparation of the film and running it through the transmitter is exactly like the ordinary film.

Fig. 5 shows the system for reception and reproduction of the colored motion pictures which includes a driving mechanism, light system and 60 general layout similar to the transmitter except that all of the film apparatus is omitted. A high frequency arc or any satisfactory form of glow discharge tube 40 may be employed as the light source. The amount of light emitted by 65 this lamp varies in proportion to the modulation of the carrier wave and therefore corresponds to the amount of light passed by the transmitting scanner through the varying density of the film in the transmitter. The scanning wheel 22 rotates in synchronism with the transmitter scanning wheel and therefore the beam of light occupies the same relative position on the receiving screen at each instant. The projection lens mounting 11 is movable in and out so that the 70 75 80 85 90 95

images may be focused properly on a receiving screen of varying dimensions. A rotating color filter 44 is shown revolving in front of the projector lens system. This is operated by suitable mechanical connection 43 to the driving motor 5. There are two color screens in this element. The screens are made of two compensated complementary colors which give the effect to the eye of natural colors. This two part screen rotates at one half the speed of the standard scanning wheel 22, showing alternate pictures through the different colored portions of the screen. The filter 44 may be located anywhere in the light path but it is convenient to place it where it may be removed if monochrome pictures are preferred or if at any time ordinary instead of colored motion pictures are being sent out by the transmitter.

As the scanning element 22 makes the first revolution the first colored screen is in the light beam, as it makes the second revolution the second colored screen is in the light beam so that successive pictures are colored alternately by the screens and the effect of naturally colored pictures is given to the spectator as the effect of the first is retained and combined with the effect of the second.

The manner in which synchronism of the transmitter and receivers is obtained when the receivers and transmitter operate on the same system of electric current supply of 60 cycles, synchronism inherent in the 60 cycle supply can usually be depended upon. This is largely true in stations that are interconnected in super power systems. Ordinary 60 cycle synchronous motors may be used and the scanning wheel adjusted around its axis, until the picture became sharp, and then fixed in this position. For space radio and where the 60 cycle motors do not operate on the same system another method must be used to periodically correct for any tendency to get out of step. This method employs a synchronizing impulse in the form of modulated high frequency energy during the period that the picture "frame" is being moved, the opaque section shutting off the light beam and no light impulses being transmitted. In the transmitter a coil of wire connected through an amplifier to the modulation circuit, is mounted in close proximity to the scanning wheel. An electro magnet or a permanent magnet is mounted on the scanning wheel so that the coil and magnet will be in close proximity when the light is obstructed by the opaque portion of the rim. As the magnet is turned past the stationary coil there is generated an electrical impulse in the stationary coil. This impulse is amplified and caused to modulate the carrier energy of the transmitter. This impulse is received and amplified and caused to energize a similar coil in the receiver. The energization of the coil in the receiver will act on a similar electro magnet or permanent magnet in the scanning wheel of the receiver and retard or advance the scanning wheel. Thus a synchronizing impulse will be exerted during each revolution of the scanning wheel during the interval when no picture is being transmitted. Sound could also be recorded on the motion picture film to be transmitted and at the receiving station the pictures in natural colors could be reproduced accompanied by the reproduced sound.

It is obvious that many systems for the transmission and reception of motion pictures may be

employed without departing from the spirit of my invention, and I do not intend to limit my invention to the foregoing specification or to the accompanying drawings but only as shown by the scope of the appended claims.

What I claim as new and desire to secure by Letters Patent of the United States is as follows:

1. In a system for transmitting motion picture films having successive pictures thereon separated by a frame line on the film, means for moving the film subject to be transmitted in one direction past a predetermined point, means for projecting a light beam through said film in a line for line manner along straight paths parallel to the path of motion thereof, and means including a rectangularly apertured mask for obstructing said light beam at the borders of the picture frame.

2. A method of scanning differently characterized latent color frames of a color motion picture film which comprises projecting a beam of light along rectilinear lines within one color characterized framed portion of said film while stationary, subsequently moving the film to permit a succeeding and differently color characterized frame to be scanned, and interrupting the scanning operation while the motion picture film is being moved from one latent color frame to the next.

3. In a system for the transmission and reception of motion pictures means including an apertured scanning drum for directing beams of light successively through elemental portions of a succession of different color component frames of a latent color motion picture film along rectilinear scanning lines, a light responsive device acted upon by said beams of light for translating the scanning operation into television signals, and receiving apparatus comprising means responsive to said signals for modulating a beam of light, a scanning drum for distributing said beam successively along rectilinear scanning lines and over elemental portions of a visible screen, and a color filter adapted to move in synchronism with said receiving drum for imparting one color to all of the modulated light corresponding to one of said transmitted frames and another color to the modulated light corresponding to another of said transmitted frames.

4. A television system in accordance with claim 3 in which a source for the first said light beams is provided internally of the first said scanning drum and the scanned area of said film is disposed closely adjacent the periphery of said drum.

5. A television system in accordance with claim 3 in which the apertures of each said scanning drum are disposed about a portion of the periphery thereof and the remainder of said periphery is totally opaque for obstructing the light beam during the time interval in which successive pictures are moved into scanning position.

6. A television system in accordance with claim 3 in which successive pictures of said film are moved in one direction intermittently, and the apertures of said scanning drum are arranged to direct said beams of light along rectilinear scanning lines which are parallel to the direction of motion of said film and so that the scanning of said film is performed only when the scanned picture area thereof is stationary.

7. A television apparatus comprising, a source of signal controlled irradiations, a rotatable scanning element for successively defining said irra-

diations into the elemental areas of a picture, a rotatable color screen for characterizing the irradiations so defined with different colors, a motor for driving said rotatable scanning element at a predetermined speed, and reduction gears intercoupling said motor and said color screen for driving said color screen at a reduced rate of speed for characterizing different consecutive groups of elemental areas of a picture with different colors, said rotatable scanning element including means for periodically masking said irradiations from the field of view for a predetermined interval between the changes of said irradiations from one color characterization to another.

8. Television apparatus comprising, a signal controlled source of light, a scanning drum having apertures therein for rectilinearly defining said light into different consecutive picture elements, a rotatable color filter for imparting different color characteristics to the irradiations defined by said drum, a mechanical coupling between said filter and said drum for permitting the rotation of said drum and said filter at different relative speeds, and a motor for driving said drum and said filter, said drum being constructed to mask the light from said source when said filter changes from one color characteristic to another.

CLINTON W. HOUGH. 15
